UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

1,337,712.

Specification of Letters Patent. Patented Apr. 20, 1920.

Application filed October 10, 1917. Serial No. 195,718.

To all whom it may concern:

Be it known that I, ALBEN E. LUNDELL, a citizen of the United States, residing at New York, in the county of Bronx and State of New York, have invented certain new and useful Improvements in Telephone Systems, of which the following is a full, clear, concise, and exact description.

This invention relates to telephone systems, and more particularly to the control of signaling means employed in telephone systems.

In semi-automatic telephone systems, especially calls from a semi-automatic to a manual office, it is necessary to indicate to the B operator the number of the called subscriber's line. In the present practice, it is customary to indicate the number of the called subscriber by the display of a set of properly arranged lamps before said B operator. The lighting of the lamps of this set is controlled by a sending device operated by the answering or A operator. In the operation of this number-indicating or displaying means, it is essential that the set of lamps before a B operator shall be released immediately from a trunk as soon as the B operator has connected said trunk to the called line, in order that another trunk may immediately seize and actuate said set of lamps.

The main feature of this invention resides in the provision of means to immediately release the set of indicator lamps as soon as the trunk with which it is associated has been plugged into the jack of the called line. Heretofore, it has been necessary to wait until the trunk sequence switch has rotated into the proper ringing position before the lamps were released. The drawings, with Fig. 1 placed above Fig. 2, Fig. 2 placed above Fig. 3, and Fig. 4 placed at the left of Fig. 3, diagrammatically represent a portion of a telephone system employing the present invention. Fig. 1 diagrammatically represents indicators or circuit-controlling devices for the number lamps. Fig. 2 diagrammatically represents a trunk finder, an allotter for allotting any one of a plurality of trunk finders for use, and a lamp allotter for associating a set of number lamps, of which only one set is shown, with a trunk

on which a call has originated. Fig. 3 diagrammatically represents a trunk, a B operator's cord circuit and a called line. Fig. 4 55 diagrammatically represents a calling line, an A operator's cord circuit, a selector switch for extending the calling line to the B operator's position, and a sender for controlling the selector switch and the indicators. 60

Within the dotted rectangle at the extreme right of Fig. 2, there is indicated an allotter. This allotter is common to a plurality of trunk finders and operates to select an idle trunk finder to care for the next call that is originated. At the left of this allotter, there is a second dotted rectangle within which there is indicated an allotter. This allotter is also common to a plurality 70 of trunk finders and operates to associate an idle set of number indicating lamps with a trunk on which a call has originated.

The indicators, allotters and sequence switches employed in the system are similar in structure to the sequence switch disclosed in Reynolds-Baldwin Patent No. 1,127,808, and are similar in operation and function to the sequence switches disclosed in McBerty Patent No. 1,125,579. 80

The trunk finder of this system is similar in structure to the switch disclosed in Craft-Reynolds Patent No. 1,123,696.

In this description, reference will be made to a fundamental circuit. This fundamental circuit includes a stepping relay, which actuates counting devices under the control of registers (not shown), set by the A operator in initiating a call. A complete disclosure of the fundamental circuit, and 85 of the stepping relay and registers, will be found in the patent to Lundell, No. 1,168,319.

When the subscriber at substation S removes his receiver from the hook, a circuit 95 for line relay 10 is completed from grounded battery, left-hand winding of relay 10, outer armature and back contact of relay 11, apparatus at substation S, inner armature and back contact of relay 11, right-hand 100 winding of relay 10, to ground. Relay 10, completes a circuit for lamp 12. The A operator, seeing the lighted lamp 12, inserts the plug 14 of an idle cord circuit,

2
into the jack 13 of the calling line. After ascertaining the number of the called party, in a manner not shown but well known in the art, the A operator operates a keyboard 5 (not shown) to control the selector switch 50 and the indicators shown in Fig. 3. A complete description of the operation of the selector switch 50 may be obtained from the Lundell patent, No. 1,168,319, above mentioned.

As soon as the brushes 51, 52 of the selector switch 50 engage the terminals 302 and 304 of an idle trunk leading to the B operator's position, the fundamental circuit 15 is extended to the line relay 306. This circuit may be traced from grounded battery, contact 307, winding of relay 306, contact 308, conductor 303, terminal 302, brush 51, lower contact spring 54, winding of relay 55, 20 back contact and armature of O' counting relay, contact spring 56, lower contact of spring 57, conductor 58, brush 52, terminal 304, conductor 305, contact 309, to ground. Relay 306 becomes energized and completes 25 a circuit from grounded battery, power magnet of sequence switch 300, contact 310, right-hand front contact and armature of relay 306, to ground, to move this sequence switch into position 2. A circuit is now completed 30 to relay 201 from grounded battery, winding of relay 201, contacts 202, 203 and 311, to ground. Relay 201 attracts its armatures and completes a circuit from grounded battery, winding of power magnet of sequence 35 switch 200, contacts 205, 204, front contact of relay 201, to ground, to move the sequence switch 200 into position 2. As soon as the sequence switch 200 rotates through position 1 $\frac{1}{2}$, the relay 201 is energized over a circuit 40 from grounded battery, winding of relay 201, contacts 202 and 209, back contact and armature of relay 210, to ground. In position 2 of sequence switch 200, the circuit for the updrive magnet 206 is closed from 45 grounded battery, winding of updrive magnet 206, conductor 207, contact 208, front contact and right-hand armature of relay 201, to ground. The trunk finder switch, designated as 212, elevates its brushes under 50 control of the updrive magnet 206 until the brushes of the trunk finder 212 have reached the terminals of the trunk to which the call has been extended. As soon as the brushes engage these terminals, the relay 210 is energized over a circuit from grounded battery, 55 winding of relay 210, contacts 213, 214, 215, 216, brush 217, terminal 218, conductor 219, contact 312, to ground. Relay 210, by attracting its armature, opens the energizing 60 circuit of relay 201, but relay 201 remains energized until the brushes of the trunk finder 212 have been properly centered on the set of terminals. This holding circuit may be traced from grounded battery, wind-

ing of relay 201, front contact and left-hand 65 armature of relay 201, conductor 220, contact 221, conducting portion of the commutator 222, brush 223, to ground. When the brushes of the trunk finder have been accurately centered on a terminal set, the brush 70 223 rests on an insulated segment of the commutator 222. The relay 201 then becomes deenergized and completes a circuit from grounded battery, power magnet of sequence switch 200, contact 224, back contact 75 and right-hand armature of relay 201, to ground, to move the sequence switch into position 3, whereupon the circuit of updrive magnet 206 is opened. With the sequence switch 200 in position 3 and relay 80 210 energized, a circuit is completed from grounded battery, winding of power magnet of sequence switch 300, contacts 312, 313, conductor 314, terminal 225, brush 226, conductor 227, contacts 228, 214, front contact 85 and armature of relay 210, to ground, to move the sequence switch 300 into position 3.

Relay 306 is still maintained energized by a circuit from grounded battery, contact 307, winding of relay 306, contact 315, left-hand 90 armature and front contact of relay 306, contacts 316, 317, over the fundamental circuit previously described, to ground, through contact 309. A circuit for relay 201 is now completed from grounded battery, 95 winding of relay 201, contacts 202, 230, brush 231, terminal 232, conductor 233, contacts 318, 319, front contact and right-hand armature of relay 306, to ground. The energization of relay 201 completes a circuit from 100 grounded battery, power magnet of sequence switch 200, contacts 205, 204, front contact and right-hand armature of relay 201, to ground, moving the sequence switch 200 into 105 position 4.

The circuit for indicator 100 is now completed from grounded battery, magnet of indicator 100, contact 111, conductor 142, contact 243, conductor 220, left-hand armature and front contact of relay 201, contacts 202, 230, brush 231, terminal 232, conductor 233, contacts 318, 319, front contact and right-hand armature of relay 306, to ground. As the indicator 100 rotates 110 through its various positions, it closes the contact 109. Each time the contact 109 is closed, a circuit for shunting the stepping relay 55 in the fundamental circuit is completed from grounded battery, contact 307, winding of the relay 306, contact 315, left-hand 115 armature and front contact of relay 306, contacts 316, 320, conductor 321, terminal 234, brush 235, conductor 236, conductor 112, contact 109, conductor 110, contact 242, front contact and right-hand armature of relay 201, to ground. The indicator 100 continues to rotate, thereby shunting stepping relay 55 until the series of counting 120 125

relays (not shown) has been energized. The O' counting relay of the series of counting relays mentioned operates to interrupt the fundamental circuit, thereby causing the relay 306 to deenergize. When this relay 306 deenergizes, the relay 201 has its energizing circuit interrupted. Relay 201 deenergizes and closes a circuit for moving the sequence switch 200 into position 5. This circuit may be traced from grounded battery, magnet of sequence switch 200, contact 244, conductor 245, contacts 113, 114, 115, 116, 117, 118, conductor 120, contact 246, conductor 247, back contact and right-hand armature of relay 201, to ground. Meanwhile, such circuit changes have taken place at the sender that the counting relays are in readiness for reoperation. The fundamental circuit is again completed from grounded battery, contact 307, winding of relay 306, contacts 315, 322, 323, conductor 241, terminal 240, brush 239, conductor 238, contact 248, conductor 249, contacts 127, 106, 105, 104, 103, 102, 101, conductor 236, brush 235, terminal 234, conductor 321, contacts 320, 317, over the fundamental circuit, previously described, to ground, through contact 309. The relay 306 attracts its armatures and completes a circuit from grounded battery, winding of relay 201, contacts 202, 230, brush 231, terminal 232, conductor 233, contacts 318, 319, front contact and right-hand armature of relay 306, to ground. In position 5 of the sequence switch 200, a circuit is completed for the indicator 122. This circuit may be traced from grounded battery, magnet of the indicator 122, contact 123, conductor 124, contact 250, conductor 220, left-hand armature and front contact of relay 201, contacts 202, 230, brush 231, terminal 232, conductor 233, contacts 318, 319, front contact and right-hand armature of relay 306, to ground. As the indicator 122 rotates through its various positions, it closes the contact 125. Each time this contact 125 is closed, a shunt about stepping relay 55 of the fundamental circuit is completed. This shunt circuit may be traced from grounded battery, contact 307, winding of relay 306, contact 315, left-hand armature and front contact of relay 306, contacts 316, 320, conductor 321, terminal 234, brush 235, conductor 236, conductor 112, contact 125, conductor 110, contact 242, front contact and right-hand armature of relay 201, to ground. The indicator 122 continues to rotate until the contact 125 has caused the stepping relay 55 to successively actuate the counting relays, the number of relays actuated being determined by the setting of the registers mentioned, but not shown. When the O' counting relay has been actuated, the fundamental circuit is

again opened to cause the deenergization of the relay 306, which, in turn, causes the deenergization of relay 201, as previously described. The deenergization of relay 201 completes a circuit for moving sequence switch 200 into position 6. This circuit is completed from grounded battery, magnet of sequence switch 200, contact 251, conductor 252, contacts 126, 115, 116, 117, 118, conductor 120, contact 246, conductor 247, back contact and right-hand armature of relay 201, to ground.

The indicators 127, 128, 129 and 130 are successively operated in the same manner as described in the operation of the indicators 100 and 122. These operations are fully described in a copending application, F. N. Reeves, Serial No. 127,659, filed October 25, 1916. The setting of the various indicators controls the actuation of the sets of lamps (similar to the set 139 shown), to indicate the digits of the desired number. The set of lamps 139 is arranged to be actuated through the contacts 140 and 141 of the indicators 100 and 122, or through the contacts 140', 141', inclosed within the dotted rectangle and controlled by other indicators similar to 100 and 122.

It will be understood that the fundamental circuit is completed and the relays 306 and 201 are energized during the setting of each of these indicators. At the close of the setting of each of these indicators, the fundamental circuit is interrupted, as described, and the relays 306 and 201 are deenergized. Each time the relay 201 deenergizes, a circuit is completed to advance the sequence switch 200 one position. At the close of the setting of all the indicators, the relays 201 and 306 will be deenergized; the sequence switch 300 will be in position 3 and the sequence switch 200 will be in position 9. At this time a circuit will be completed for a sequence switch (not shown), associated with the selector 50, for causing the contact springs 54, 57 to disengage their lower contacts and to engage their upper contacts. As soon as the relay 201 deenergizes, after the last indicator has been set, a circuit is completed for moving the sequence switch 300 out of position 3 and into position 4. This circuit may be traced from grounded battery, magnet of sequence switch 300, contact 344, conductor 346, terminal 280, brush 281, conductor 283, contact 134, conductor 120, contact 246, conductor 247, back contact and right-hand armature of relay 201, to ground. In position 4 of sequence switch 300, a circuit is completed from grounded battery, contacts 331, 332, winding of relay 330, conductor 393, upper left-hand winding of repeating coil 390, conductor 303, terminal 302, brush 51, conductor 53, upper contact of spring

54, upper right-hand winding of repeating coil 70, to ground. The energization of relay 330 completes a circuit from grounded battery, contact 333, front contact and right-hand armature of relay 330, contacts 334, 5 335, conductor 336, left-hand winding of relay 337, to ground. The relay 337 attracts its armatures, and, at its right-hand armature and front contact, completes a locking 10 circuit for itself from grounded battery, contact 339, right-hand winding of relay 337, contacts 338, 313, right-hand armature and front contact of relay 337, to ground. Relay 337 is, therefore, maintained energized by the circuit until the sequence 15 switch 300 moves out of position 7. At the right-hand armature and front contact of relay 337, a circuit is also completed from grounded battery, winding of relay 210, 20 contacts 213, 228, conductor 227, brush 226, terminal 225, conductor 314, right-hand armature and front contact of relay 337, to ground. The energization of relay 210 completes a circuit from grounded battery, magnet 25 of sequence switch 200, contact 253, front contact and left-hand armature of relay 210, to ground. This circuit operates to move the sequence switch 200 out of position 9 and into position 10. As soon as the sequence switch 200 leaves position 9, the circuit of relay 210 is opened through contact 213. In position 10, the circuit for relay 201 is completed from grounded battery, winding of relay 201, contacts 254, 228, conductor 227, brush 226, terminal 225, conductor 314, right-hand armature and front contact of relay 337, to ground. The deenergization of relay 210, previously described, completes a circuit for moving the 30 sequence switch 200 out of position 10 and into position 11. The circuit is traced from grounded battery, magnet of sequence switch 200, contact 255, back contact and armature of relay 210, to ground. As soon as the sequence switch 200 reaches position 10, with the relay 201 energized, the relay 256, which controls the setting of the lamp allotter 261, is energized over a circuit from grounded battery, winding of relay 256, contact 35 257, resistance 259, contact 260, conductor 220, left-hand armature and front contact of relay 201, contacts 254, 228, conductor 227, brush 226, terminal 225, conductor 314, right-hand armature and front contact of relay 337, to ground. Relay 256, by attracting its armature, opens a breakpoint in the operating circuit of the allotter 261 for a purpose hereinafter described. This relay 50 256 is maintained energized until the sequence switch 200 moves out of position 14. With the sequence switch 200 in position 11 and with relay 256 energized, a circuit is completed from grounded battery, winding of relay 210, contacts 267, 268, 269, back contact and armature of relay 264, front contact 65 and armature of relay 256, contact 263, front contact and right-hand armature of relay 201, to ground. Relay 210 attracts its armatures, and completes a circuit from grounded battery, winding of magnet of sequence 70 switch 200, contact 253, front contact and armature of relay 210, to ground, for moving the sequence switch 200 into position 12. As soon as the sequence switch 200 reaches 75 position 12, a circuit is completed from grounded battery, winding of relay 264, conductor 265, contact 131, conductor 145, contact 266, to ground. Relay 264, by attracting its armature, prevents any other relay similar to relay 210 from being energized 80 when the allotter picks up the finder with which such relay is associated, as will hereinafter be described. When the relay 264 attracted its armature, it opened the energizing circuit of relay 210. The deenergization of relay 210 completes a circuit from grounded battery, magnet of sequence switch 200, contact 255, back contact and armature of 85 210, to ground, for moving the sequence switch 200 into position 15. As soon as the sequence switch 200 reached position 14, a circuit was completed from grounded battery, magnet of indicator 122, contact 180, conductor 181, contact 299, to ground, for moving the indicator 122 into position 4. 90 In position 14 of sequence switch 200, a circuit is also completed from grounded battery, contact 325, winding of relay 324, contacts 326, 318, conductor 233, terminal 232, brush 231, contacts 230, 209, back contact 100 and armature of relay 210, to ground. The energization of relay 324 completes a circuit from grounded battery, left-hand armature and front contact of relay 324, contact spring 327, contact 328, winding of relay 306, contact 329, to ground. Relay 306 becomes energized and completes a circuit from grounded battery, magnet of sequence switch 300, contact 310, front contact and right-hand armature of relay 306, to ground, moving the sequence switch 300 out of position 105 4 and into position 7. As soon as sequence switch 200 leaves position 14, the holding circuit of relay 256 is opened at contact 260. Relay 256 deenergizes and closes the circuit 110 of power magnet of sequence switch 261 to conductor 284. As soon as another cord finder sequence switch reaches positions 11 and 12, the circuit of power magnet of sequence switch will be completed at the right-hand armature and front contact of a relay similar to 201, and the lamp allotter 261 will be rotated until it reaches a position to associate this next trunk with the set of lamps. As soon as this position is reached 115 relay 256 becomes energized over a circuit similar to the one described. But the sequence switch of the next cord finder is not 120 125

5 moved out of position 12 until relay 264 is deenergized and thereby prevents the operation of the lamps by the indicators associated with the second cord finder until the preceding call has been erased. In position 15 of sequence switch 200, the relay 201 is still maintained energized by circuit from grounded battery, winding of relay 201, front contact and left-hand armature of 10 relay 201, conductor 220, contact 298, brush 226, terminal 225, conductor 314, right-hand armature and front contact of relay 337, to ground.

15 The movement of the indicator 122 in position 4 completes a circuit of the lamps associated with the indicators 100, 127, 128, 129 and 130 to display the number of the desired line in front of the B operator. The B operator then inserts the plug 341 20 into the jack 394 of the called line. A circuit is then completed from grounded battery, winding of relay 342, sleeve of plug 341, sleeve of jack 394, winding of cutoff relay 395, to ground. Since the sequence 25 switch 300 is in position 7 at this time, the relay 337 is still maintained energized, so that the energization of relay 342 completes a circuit from grounded battery, magnet of indicator 122, contact 182, conductor 112, 30 conductor 236, brush 235, terminal 234, conductors 321, 396, front contact and left-hand armature of relay 337, conductor 353, front contact and lower armature of relay 342, to ground. This circuit causes the indicator 122 to move into position 5. When the indicator 122 leaves position 4, the circuit for relay 264 is opened at contact 131 to allow the next trunk finder sequence switch 35 to move out of 11 to utilize the lamp set. In position 5 of indicator 122, a circuit is completed from grounded battery, magnet of sequence switch 300, contact 344, conductor 346, terminal 280, brush 281, contact 297, conductor 296, contact 295, conductor 112, 45 conductor 236, brush 235, terminal 234, conductors 321, 396, front contact and left-hand armature of relay 337, conductor 353, front contact of lower armature of relay 342, to ground, for moving the sequence switch 300 50 out of position 7 and into position 8. As soon as the sequence switch 300 leaves position 7, the locking circuit for relay 337 is opened. The deenergization of this relay 337 opens the locking circuit of relay 201. 55 The deenergization of relay 337 also completes a circuit from grounded battery, contact 333, front contact and armature of relay 330, contacts 353, 352, conductor 351, winding of ringing relay 349, back contact 60 and armature of relay 359, conductor 358, back contact and armature of relay 337, conductor 353, front contact and lower armature of relay 342, to ground. Relay 349 attracts its armature to apply ringing cur-

rent through the winding of relay 359, contact 360, front contact and lower armature of relay 349, ring of plug 341, ring of sleeve 394, apparatus at the called substation, tip of jack 394, tip of plug 341, upper armature and front contact of relay 342, upper armature and front contact of relay 349, contact 361, to ground. Relay 359 is marginal and does not attract its armature until the called subscriber has removed his receiver from the switchhook. Relay 359 thereupon attracts 75 its armature and removes the shunt from around relay 350. Relay 350 becomes energized and completes a locking circuit for itself from grounded battery, contact 333, front contact and armature of relay 330, 80 contacts 353, 352, front contact and upper armature of relay 350, winding of relay 350, conductor 358, back contact and left-hand armature of relay 337, conductor 353, front contact and lower armature of relay 342, to 85 ground. The energization of relay 350 also opens the circuit of relay 349.

As soon as the relay 201 deenergizes, when its energizing circuit is interrupted by the deenergization of relay 337, a circuit was 90 completed from ground, magnet of sequence switch 200, contact 224, back contact and right-hand armature of relay 201, to ground, for moving the sequence switch 200 into position 16. As soon as sequence switch 200 reaches position 16, the indicator 100 is restored to its normal position, over a circuit completed from grounded battery, magnet of indicator 100, contact 135, conductor 136, contact 285, conductor 247, back contact and 95 right-hand armature of relay 201, to ground.

100 The indicator 122 is restored in a similar manner over a circuit completed from grounded battery, winding of indicator 122, contact 142, conductor 143, contact 286, conductor 247, back contact and right-hand armature of relay 201, to ground. The indicator 127 is restored to its normal position over a circuit established through grounded battery, magnet of indicator 127, contact 110 137, conductor 138, contact 287, to ground. The indicators 128, 129 and 130 are restored in a similar manner by circuits completed through contacts 288, 289, 290, respectively. In position 16 of the sequence switch 200, a 115 circuit is also completed for the downdrive magnet 274, from grounded battery, winding of magnet 274, contact 271, to ground. As soon as the trunk finder switch reaches its normal position, the commutator brush 120 272 engages the conducting segment 273, thereby completing a circuit from grounded battery, magnet of sequence switch 200, contact 275, conducting segment 273, commutator brush 272, to ground, moving 125 the sequence switch 200 into position 17. As soon as the indicators have reached their normal positions, and sequence switch 200

has reached position 17, sequence switch 200 is moved into position 18 by the following circuit, grounded battery, magnet of sequence switch 200, contact 276, conductor 277, contacts 132, 114, 115, 116, 117, 118, conductor 120, contact 246, conductor 247, back contact and right-hand armature of relay 201, to ground.

At the termination of the conversation, 10 the sequence switch, associated with the selector shown in Fig. 4, is moved out of position 16, in the well-known manner, thereby causing the deenergization of relay 330. The deenergization of relay 330 causes the deenergization of relay 324, which, in turn, 15 causes the deenergization of relay 306. Relay 306, by retracting its right-hand armature, completes a circuit from grounded battery, magnet of sequence switch 300, contact 355, back contact and right-hand armature of relay 306, to ground, to move the sequence switch 300 into position 9. In position 9, the disconnect lamp 362 is lighted 20 in a circuit which may be traced from grounded battery, lamp 362, contact 363, to ground. The B operator, on noting the lamp 362, removes the plug 341 from jack 394 of the called line. Relay 342 deenergizes 25 and completes a circuit from grounded battery, magnet of sequence switch 300, contact 364, back contact and lower armature of relay 342, to ground. The sequence switch 300 now moves into its normal position and 30 the apparatus is in condition for the next call.

What is claimed is:

1. In a telephone system, an incoming line, an outgoing line, means for connecting said incoming line to said outgoing line, a 40 source of ringing current, a variably operable signal, means for associating said signal with said incoming line, means operated by the connection of said incoming line with said outgoing line for disassociating said signal from said incoming line, and means operated in disassociating said signal from said incoming line for connecting said source of ringing current to said outgoing line.

2. In a telephone system, an incoming 50 line, an outgoing line, means for connecting said incoming line to said outgoing line, a source of ringing current, a signal, a switching device for controlling said signal, means associated with said incoming line for operating said switching device to associate said signal with said incoming line, means operated by the connection of said incoming line with said outgoing line for operating said switching device to disassociate said signal from said incoming line, and means operated by the last-mentioned operation of said switching device for connecting said source of ringing current to said outgoing line.

3. In a telephone system, an incoming

line, an outgoing line, means for connecting said incoming line to said outgoing line, a circuit controlling device controlling the connection between said lines, a variably operable signal, means for associating said signal with said incoming line, means operated by the connection of said incoming line with said outgoing line for disassociating said signal from said incoming line, and means operated in disassociating said signal from said incoming line for operating said circuit controlling device to complete the connection between said lines.

4. In a telephone system, an incoming line, an outgoing line, means for connecting said incoming line to said outgoing line, a 80 circuit controlling device controlling the connection between said lines, a signal, a switching device for controlling the operation of said signal, means associated with said incoming line for operating said switching device to associate said signal with said incoming line, means operated by the connection of said incoming line with said outgoing line for operating said switching device to disassociate said signal from said incoming line, and means operated by said last-mentioned operation of said switching device for operating said circuit controlling device to complete the connection between 85 said lines.

5. In a telephone system, an incoming line, an outgoing line, means for connecting said incoming line to said outgoing line, a sequence switch for controlling the connection between said lines, a signal, a second sequence switch for controlling the operation of said signal, means associated with an incoming line for operating said second sequence switch to associate said signal with said incoming line, means operated by the connection of said incoming line with said outgoing line for operating said second sequence switch to disassociate said signal from said incoming line, and means operated by the last-mentioned operation of said 100 second sequence switch for operating said first-mentioned sequence switch.

6. In a telephone system, incoming lines, outgoing lines, an operator's position in which said lines terminate, a signal at said position, a switching device for controlling the operation of said signal, means associated with an incoming line for operating said switching device to cause said signal to indicate the desired outgoing line, means 115 under the control of the operator for connecting the incoming line to the desired line, a circuit controlling device for controlling the connection between said lines, means operated by the connection of said incoming 120 line with said outgoing line for operating said switching device for discontinuing the actuation of said signal, and means operated 125

by the last mentioned operation of said switching device for operating said circuit controlling device to complete the connection between said lines.

5 7. In a telephone system, incoming lines and outgoing lines, means for connecting an incoming line to an outgoing line, a source of ringing current, a signal common to said incoming lines, means for associating said 10 signal with an incoming line, means oper-

ated by the connection of said incoming line with said outgoing line for disassociating said signal, and means operated in disassociating said signal for connecting said source of ringing current to said outgoing 15 line.

In witness whereof I hereunto subscribe my name this 4th day of October, A. D. 1917.

ALBEN E. LUNDELL.
